UNITED STATES PATENT OFFICE

SIEGFRIED BEHR, OF NEW YORK, N. Y.

DESIGN FOR A GAME BOARD

Application filed July 24, 1931. Serial No. 40,668. Term of patent 7 years.

To all whom it may concern:

Be it known that I, SIEGFRIED BEHR, a citizen of the United States, residing at 4116 169th Street, Flushing, L. I., N. Y., in the county of Queens and State of New York, have invented a new, original, and ornamental Design for a Game Board, of which the following is a specification, reference being had to the accompanying drawings, forming part thereof, in which Fig. 1 represents a plan view, and Fig. 2 represents a side elevation of my game board.

I claim:

The ornamental design for a game board as shown.

SIEGFRIED BEHR.
